UNITED STATES PATENT OFFICE.

GUSTAV B. PETSCHÉ, OF PHILADELPHIA, PENNSYLVANIA, ASSIGNOR TO THE SOUTHWARK FOUNDRY & MACHINE COMPANY, OF PHILADELPHIA, PENNSYLVANIA, A CORPORATION OF PENNSYLVANIA.

GOVERNOR.

SPECIFICATION forming part of Letters Patent No. 736,542, dated August 18, 1903.

Application filed July 18, 1902. Serial No. 116,019. (No model.)

To all whom it may concern:

Be it known that I, GUSTAV B. PETSCHÉ, a subject of the Emperor of Germany, residing in the city and county of Philadelphia, in the State of Pennsylvania, have invented a certain new and useful Improvement in Governors, of which the following is a true and exact description, reference being had to the accompanying drawings, which form a part thereof.

My invention relates to governors for steam-engines, and has for its object to provide for a construction whereby the governor can be readily detached from its actuating mechanism and whereby also the valve controlled by the governor can be adjusted and set to any desired permanent position.

With these objects in view my invention consists in constructing a governor with a rotatable and longitudinally-movable spindle, which in normal position is actuated by a moving part of the engine, and providing means for shifting the spindle longitudinally to disconnect it from the operative mechanism and also through the motion of the spindle to adjust and set the controlled valve upon which the governor normally operates.

The nature of my improvements will be best understood as described in connection with the drawings, in which they are illustrated, and in which—

Figure 1 is a side elevation of the governor embodying my improvements. Fig. 2 is a plan view thereof; and Fig. 3, a side elevation of another modified construction, also embodying my improvements.

In the construction shown in Figs 1 and 2 the governor is supported on a base Q, having a laterally-extending platform Q' and arch-like arms Q², springing from the ends of this platform and supporting the bearing Q³, in which the spindle turns. L indicates the spindle, vertically supported in the bearing Q³ and having at its lower end a friction-disk L', which normally rests in contact with a friction-wheel N, keyed to a shaft N', which has also secured to it a pulley N², about which passes a belt N³, operated by some moving part of the engine. (Not shown.)

50 The friction-wheel N is free to move longitudinally

55 on the shaft N' and is adjusted to position by means of the arm R³, attached to its hub and having a threaded perforation through which it screws to the rod R, actuated by a hand-wheel R' and supported by arms R² R³. L² indicates the usual weights, pivoted to the spindle L and connected to a sleeve L³, which slides upon the shaft and has attached to it a collar L⁴, through which motion is communicated to the bell-crank lever M and to the connecting-rod M', which in turn communicates with the valve controlled by the governor, but not shown in the drawings. L¹ indicates a collar secured to the spindle L and upon which the sleeve L³ can rest 60 when the governor is not in normal operation. L² indicates another collar secured to the spindle L and lying within a threaded thimble p, which is secured to the lower part of the bearing Q³ and in which screws the 65 perforated adjusting-screw O, having a hand-wheel O'.

In the modification shown in Fig. 3 the longitudinally-adjustable spindle has its friction-disk L' secured to its top and resting on a 75 friction-wheel N, driven from the engine, as in the first-described apparatus. The spindle turns and is longitudinally movable in bearings S' and S² and is longitudinally adjusted by means of an adjusting-screw O, 80 working in a threaded bearing S³ and actuated by a hand-wheel O'. In other respects the devices are practically alike and are essentially alike in their mode of operation.

In operation the adjusting-screw O is retracted, so that it does not support the spindle L, the weight of which is supported through the friction-disk L' upon the friction-wheel N, and the governor operates in the usual manner, the speed of rotation of the spindle 90 regulating the rise and fall of the weights L², which through the sleeve and collar L³ L⁴ act upon the controlling-valve. When it is desired to disconnect the governor from the operative mechanism, the screw O is turned up, so as 95 to engage and lift the spindle, thereby carrying the friction-disk out of contact with the friction-wheel and throwing the governor out of operative connection. The setting of the controlled valve is effected by the simple ex- 100

pedient of still further screwing up the screws O, the lifting of the spindle being communicated through the collars l' or any other convenient device or connection to the sleeve L³ 5 and through it communicated to the valve, as in the case of normal operation.

It will be understood that, save where expressly so limited in the claims, my invention is not limited to the use of friction devices 10 for giving motion to the spindle, for any detachable connection disengaged by lifting the spindle will serve the same purpose.

Having now described my invention, what I claim as new, and desire to secure by Letters 15 Patent, is—

1. A steam-engine governor, having in combination, a spindle, rotatable and longitudinally movable in its bearings, means for driving the spindle, operative when the spindle 20 is in normal position, weights secured to the spindle and operated by it, a sleeve connected to said weights and coupled to operate a regulating-valve, and means for shifting the spin-

dle and sleeve longitudinally to disconnect the governor from the actuating mechanism 25 and to adjust the sleeve and its valve connections to a determined position.

2. A steam-engine governor, having in combination, a rotatable and longitudinally-movable spindle, a friction-wheel driven by the 30 engine, a friction-disk secured to the spindle and adapted to be supported on and driven by the friction-wheel, weights secured to and driven by the spindle, a longitudinally-movable sleeve connected to the weights and sliding on the spindle, valve connections actuated by said sleeve, and means for raising the spindle and, through it, the sleeve, to lift the friction-disk out of operative position on the friction-wheel, and to adjust the valve connection when the governor is out of operation. 35

GUSTAV B. PETSCHE.
